(57) **CLAIM**

The ornamental design for a watch movement, as shown and described.

DESCRIPTION

1. Watch movement

1.1 is a front view of a watch movement;

1.2 is a back view thereof;

1.3 is a right side view thereof;

1.4 is a left side view thereof;

1.5 is a bottom view thereof;

1.6 is a top view thereof;

1.7 is a front perspective view thereof;

1.8 is another front perspective view thereof; and

1.9 is a back perspective view thereof.

The portions of the watch movement shown in broken lines form no part of the claimed design.
